UNITED STATES PATENT OFFICE

2,419,774

MANUFACTURE OF YARN

Malcolm Hain, Montclair, N. J.

Application March 15, 1946, Serial No. 654,704

2 Claims. (Cl. 19—130)

1

This invention relates to sliver-drawing apparatus of the same class as that set forth in my Patent No. 2,197,638. In my said patented apparatus, between the pairs of drawing and retaining rolls there is a single driven roll and the means cooperative therewith to control the draft includes two pressure rolls which, during the actual drawing, are both held in sliver-gripping relation to the driven roll. In the apparatus of the present invention the driven roll is replaced by a pair of driven rolls and the two pressure rolls are replaced by a single pressure roll which, during the actual drawing, is held in sliver-gripping relation to such two driven rolls. Further, instead of the pressure required for gripping the sliver being attained by resort to a lever-and-carrier system of the type disclosed in my said patent, a lever-and-carrier system of the type disclosed in my copending application Serial No. 609,531 is employed. The apparatus as thus constructed involves certain advantages as compared to the apparatuses of my said patent and application which will be hereinafter explained.

In the drawings,

Fig. 1 is a side elevation, partly in section, of a portion of a sliver-drawing apparatus constructed in accordance with my present invention;

Fig. 2 is an elevation of a part of the gearing as viewed from the right in Fig. 1;

Fig. 3 is a plan of a driven roll and the pressure rolls of two adjoining drawing units; and

Fig. 4 is a plan of the carrier and a fragment of the weighted lever by which it is partly supported.

The drawing rolls 1—1a and retaining rolls 2—2a are substantially the same in construction and function as in my said patent, as are also the following parts: the spout 3 through which the sliver a passes to the drawing rolls; the weighted lever 4 (forming with the frame a part of the supporting structure) for holding the roll 2a against roll 2; and the parts mounted on the portion 5 of the frame, as lever 6, link 7, bell-crank lever 8 and depending link 9 which at 9a is adapted for lifting lever 4 when lever 6 is moved to coat with a fixed member 10 to clamp the sliver. On the frame portion 5 is the usual guide 11 for the sliver.

Between the rolls 1—1a and 2—2a is arranged a pair of superposed shafts 12, here with their axes in a common vertical plane. They are assumed to be driven at the same speed but such as will be between the speeds of the rolls 1—1a and 2—2a, they having reduced portions, as 12a, providing journals received in bearings 13 of 55

the frame. They provide what I term driven rolls.

At 14 is a pressure roll. This is journaled in the forked terminals of a forked carrier 15 which is pivoted at its rear end to the depending forward arm 16a of a lever 16 fulcrumed at 17a in a bracket 17 fast to a portion 18 of the frame and having a depending rear arm carrying a weight 19. The fork at 15a of carrier 15 serves to guide the sliver. The carrier at 17b is slidably supported by bracket 17 and so is subject to forward thrust by lever 16. The carrier has what I term bearing means 15b for the trunnions 14a of the pressure roll and which face the latter, and forward of such means it has surfaces 15c forming a guideway for the trunnions and which slopes downwardly toward said roll so that normally or even when the carrier is retracted, said roll (by its own weight) is urged to coat with the driven rolls to grip the sliver.

20 The shaft 1x of roll 1 being suitably driven, a gear I thereon drives a gear II forming a unit with a smaller gear III which drives a gear IV fast to the shaft 2x of retaining roll 2 and formed as a unit with a smaller gear V which drives a gear VI 25 formed as a unit with a larger gear VII which drives the gears VIII—VIII having the same pitch-diameter and fast to the rolls 12 and lapping each other (Fig. 1), the gearing being thus such that the retaining rolls will be driven more slowly than the drawing rolls and the driven rolls 12 and pressure roll 14 will be driven at a speed between those of such drawing and retaining rolls.

The operation is generally similar to that of the apparatus of my said patent as will be evident to those skilled in this art, but it involves these further advantages in respect to the group of three rolls between the drawing and retaining roll pairs: In the first place, since two of such rolls, instead of only one, are driven such group of rolls acts more effectively to control the sliver and hence what I have in my said patent termed the "va-grant" fibers thereof. In the second place, one of the three rolls being of larger diameter than the other two thus to obtain an extended tractive contact with the sliver, since such roll is in the present instance the (single) pressure roll possibility of stray fibers becoming wound around its trunnions 14a and thus having to be removed from time to time is considerably reduced.

Having thus fully described my invention what I claim is:

1. In the art of drawing sliver, the combination, with mechanism for imparting tractive effort to the sliver including supporting structure, a pair of drawing rolls and a pair of retaining rolls jour-

naled in said structure, a pair of driven rolls journaled in said structure between said roll pairs, all said rolls being substantially parallel, and means to rotate one drawing roll and one retaining roll, the former at the superior speed, and also rotate the driven rolls at a common speed between those of the latter drawing and retaining rolls, of means coercive with said driven rolls to control the draft including a pressure roll substantially parallel with and normally urged to co-act with both driven rolls to grip the sliver, a carrier in which the pressure roll is journaled and being in part supported by said mechanism and having bearing means lateral of the path of the sliver and facing the driven rolls and abutting the pressure roll, and a lever to which the carrier is pivoted to oscillate therewith independently of the pressure roll and also supporting the carrier and normally urged in the direction to urge the carrier toward said driven rolls, said carrier having a guideway for supporting the pressure roll when the carrier is retracted.

4
2. The combination set forth in claim 1 characterized by said guideway being sloped downwardly toward one of said driven rolls.

MALCOLM HAIN.
